RUBBER GLOVE

Henry Malm, New York, N. Y.

Application October 30, 1945, Serial No. 625,520

7 Claims. (Cl. 2—168)

1

This invention relates to the production of rubber gloves for use in protection of hands in contacting fluids of various kinds and classes. More particularly, the invention deals with the production of a glove of this kind on a mould in such manner as to produce a plurality of longitudinally extending ribs or indentures in the glove in order to space part of the hand and fingers of the hand from parts of the inner surface of the glove to allow for ventilation of air through the glove, to strengthen the glove and, further, to facilitate placement of the glove upon the hand.

The novel features of the invention will be best understood from the following descriptions, when taken together with the accompanying drawing, in which certain embodiments of the invention are disclosed and, in which, the separate parts are designated by suitable reference characters in each of the views and, in which:

Fig. 1 is a view of the back of a glove arranged 20 on the mould employed for forming the same.

Fig. 2 is a face view of the palm of the glove; and

Fig. 3 is a section on the line 3—3 of Fig. 1, indicating in dot and dash lines the position of fingers in the glove structure as and when the mould 25 is removed, and omitting all background showing.

In practice, I employ a mould 10 shaped or patterned from a human hand with the hand in a slightly curved and natural position, and different from the human hand solely in providing, between the fingers, web portions, so that the resulting glove 11 will have, between the finger portions 12 and 13, a web 14; between the finger portions 13 and 15, a web 16 and, between the fingers 15 and 17, a web 18, the web running to a point substantially adjacent the outer joints of the fingers. The webs 14, 16 and 18 will form, 30 between the fingers of the hand, air spaces 19, 20 and 21, respectively, as will clearly appear from a consideration of Fig. 3, in which figure, the four fingers have been outlined in dot and dash lines at 22, 23, 24 and 25.

The mould 10 has, on the back portion thereof, a plurality of grooves 26, 27, 28, 29 and 30 which extend from the wrist portion of the mould to a point short of the finger knuckles and, then, each groove has diverging branches 26a, 27a, 28a, 29a and 30a which extend to a point just short of the tips of all of the fingers. The grooves 26—30, inclusive, form on the resulting glove 11 inwardly depressed ribs 31, 32, 33, 34 and 35, respectively. The diverging branches 26a—30a, inclusive, form corresponding diverging inwardly directed ribs 31a, 32a, 33a, 34a and 35a. These 45 ribs serve to partially space the fingers from the surface of the glove to permit air to extend into, as well as out of the glove and to enter the spaces 19, 20 and 21. This facilitates ventilation of the glove and also mounting of the glove upon the hand, allowing the air within the glove to be exhausted in the operation of inserting the hand into the glove.

10

The palm portion of the mould also has a longitudinal groove 36, note Fig. 3, which extends from the wrist portion to and short of the tip of that part of the mould which forms the finger 15 of the glove. The groove 36 forms a corresponding inwardly extending rib 37.

15

The thumb portion of the glove is shown at 38 and this thumb portion is formed in its conventional arrangement with the hand and exclusive of any webbing, so as to allow the thumb to flex freely in grasping objects. While the fingers are maintained substantially in a close environment one with respect to the other, the web portions 14, 16 and 18 will facilitate slight spreading of the fingers, particularly in the operation of grasping objects in the hand. However, in most instances, 20 the spreading of the fingers is not essential. The resulting glove structure is a modified form of mitten, the tips or outer end portions of the fingers being free, thus enabling the tips of the fingers to have a relative movement one with respect to the other, as and when this is desired.

25

In forming the glove, the body of rubber is applied to the mould in any of the known processes and one known procedure which is probably preferable would be to use the dipping process so as to provide a substantially even wall thickness throughout the entire glove, excepting that the slight enlargement in wall thickness may result in the rib portions 31—35 and 37. This will be desirable, however, as it will give to the glove a reinforcement which will take up the stress and strain of pulling the glove upon the hand, as well as in removal of the glove from the hand. These reinforcing members will prevent tearing of the glove to a large degree and will also facilitate reducing wall thickness of the remainder of the glove, so that the glove as a whole would become more comfortable upon the hand. By spreading or diverging the ribs to the sides of the fingers and thumb, in the manner shown, the joints or knuckles will be free to extend themselves in the 30 operation of bending the hand.

35

In other words, this will produce no discomfort to the wearer as would otherwise be the case, if the ribs were disposed upon the high points of the joints or knuckles. Furthermore, this con- 45

2

struction spreads the reinforcement and opens the air channels which would be formed at opposite sides of the ribs to the spaces 19, 20 and 21.

The single rib 37 on the palm of the hand serves to ventilate this portion of the hand and this rib will not, by reason of its location, materially interfere with the use of the hand in grasping objects.

At the end of the wrist portion of the mould 10 is formed a threaded socket 38 which facilitates mounting of the mould upon a suitable support in the operation of moulding and vulcanizing the glove thereon. For sake of description, the glove, in addition to the finger and thumb portions, includes a hand portion 40 and a wrist portion 41.

Having fully described my invention, what I claim as new and desire to secure by Letters Patent is:

1. A rubber glove comprising wrist, finger and thumb portions, the finger portions of the glove having short ends and being joined by web portions forming, within the glove between adjacent fingers, inwardly of the finger tips, air spaces, and means comprising inwardly extending ribs opening through the edge of the wrist portion and extending to the short finger ends to circulate air to said spaces when the glove is on the hand.

2. A rubber glove comprising wrist, finger and thumb portions, the finger portions of the glove having short ends and being joined by web portions forming, within the glove between adjacent fingers, inwardly of the finger tips, air spaces, means comprising inwardly extending ribs opening through the edge of the wrist portion and extending to the short finger ends to circulate air to said spaces when the glove is on the hand, and said ribs being arranged longitudinally of the wrist, hand and finger portions of the glove.

3. A rubber glove comprising wrist, finger and thumb portions, the finger portions of the glove having short ends and being joined by web portions forming within the glove between adjacent fingers, inwardly of the finger tips, air spaces, means comprising inwardly extending ribs opening through the ends of the wrist portion and extending to the short finger ends to circulate air to said spaces when the glove is on the hand, said ribs being arranged longitudinally of the wrist, hand and finger portions of the glove, and another rib extending along the wrist and hand portion onto the thumb portion of the glove.

4. A rubber glove comprising wrist, finger and thumb portions, the finger portions of the glove having short ends and being joined by web portions forming, within the glove between adjacent fingers, inwardly of the finger tips, air spaces, means comprising inwardly extending ribs opening through the edge of the wrist portion and extending to the short finger ends to circulate air to said spaces when the glove is on the hand, said ribs being arranged longitudinally of the wrist, hand and finger portions of the glove, another rib extending along the wrist and hand portion onto the thumb portion of the glove, and a rib extending longitudinally of the wrist, hand and one finger of the glove at the inner or palm portion of the glove.

5. A rubber glove comprising wrist, finger and

thumb portions, the finger portions of the glove having short ends and being joined by web portions forming, within the glove between adjacent fingers, inwardly of the finger tips, air spaces, means comprising inwardly extending ribs opening through the edge of the wrist portion and extending to the short finger ends to circulate air to said spaces when the glove is on the hand, said ribs being arranged longitudinally of the wrist, hand and finger portions of the glove, and said rib comprising single ribs extending to the base of the fingers and joining pairs of ribs extending along the back of each finger at side portions thereof.

15 6. A rubber glove comprising wrist, hand, finger and thumb portions, means joining the finger portions inwardly of the finger tips to provide a mitten-like structure at the fingers of the glove inwardly of said tips, said mitten-like structure forming passages between finger receiving portions of the glove, the back of the thumb and each finger portion having a pair of inwardly extending ribs joining a single rib at the base of the thumb and fingers, said last named single ribs 20 extending along the back of the wrist and hand portions of the glove to the free end of the wrist, and forming, when the glove is on the hand, communications opening said passages to atmosphere through the wrist portion of the glove.

7. A rubber glove comprising wrist, hand, finger and thumb portions, means joining the finger portions inwardly of the finger tips to provide a mitten-like structure at the fingers of the glove inwardly of said tips, said mitten-like structure 25 forming passages between finger receiving portions of the glove, the back of the thumb and each finger portion having a pair of inwardly extending ribs joining a single rib at the base of the thumb and fingers, said last named single ribs 30 extending along the back of the wrist and hand portions of the glove to the free end of the wrist, forming, when the glove is on the hand, communications opening said passages to atmosphere through the wrist portions of the glove, and means 35 opening through the wrist portion of the glove for ventilating the inner palm surface of the glove.
